(57) **CLAIM**

We claim the ornamental design for a “tire tread,” as shown and described.

DESCRIPTION

FIG. 1 is a perspective view of a tire tread, showing our new design;

FIG. 2 is a front view thereof;

FIG. 3 is a side view thereof; and,

FIG. 4 is an enlarged fragmentary front view thereof.

The broken line showing of a tire sidewall and inner bead, including the peripheral boundary between the claimed tread portion and the sidewall, represents unclaimed environmental subject matter.
